US0D1077655S

(12) **United States Design Patent** (10) **Patent No.:** **US D1,077,655 S**
(45) **Date of Patent:** **** Jun. 3, 2025**

(54) **CONTROLLER AND FLOW SENSOR**

(71) Applicant: **BELIMO HOLDING AG**, Ch-8340 Hinwil (CH)

(72) Inventors: **Atilla Beker**, Wetzikon (CH); **Peter Dreher**, Meilen (CH); **Walter Jungen**, Adliswil (CH)

(73) Assignee: **BELIMO HOLDING AG**, Hinwil (CH)

(**) Term: **15 Years**

(21) Appl. No.: **29/819,658**

(22) Filed: **Dec. 16, 2021**

Related U.S. Application Data

(62) Division of application No. 35/510,076, filed on Feb. 12, 2020 (U.S. filing date under 35 U.S.C. 384), and (Continued)

CLAIM

The ornamental design for a controller and flow sensor, as shown and described.

DESCRIPTION

FIG. 1 is a left side view of a controller and flow sensor, of the design shown;

FIG. 2 is a right side view thereof;

FIG. 3 is a bottom side view thereof;

FIG. 4 is a top side view thereof;

FIG. 5 is a front side view thereof;

FIG. 6 is a back side view thereof; and,

FIG. 7 is a perspective view thereof.

1 Claim, 5 Drawing Sheets

Related U.S. Application Data

having an international filing date of Feb. 12, 2020,
now Pat. No. Des. 940,578.
